UNITED STATES PATENT OFFICE.

CHARLES J. NASH, OF CHICAGO, ILLINOIS, ASSIGNOR TO UNIVERSAL DRAFT GEAR ATTACHMENT CO., A CORPORATION OF ILLINOIS.

UNDERFRAMING FOR CARS.

1,274,747.

Specification of Letters Patent. Patented Aug. 6, 1918.

Application filed October 18, 1917. Serial No. 197,249.

To all whom it may concern:

Be it known that I, CHARLES J. NASH, a citizen of the United States, residing at Chicago, in the county of Cook and State of Illinois, have invented certain new and useful Improvements in Underframings for Cars, of which the following is a specification.

The invention relates to cars in which the underframing comprises a bolster formed of an upper and a lower plate, and draft arms for reinforcing the sills and extending over and on both sides of the bolster, there being present also sub-sills back of the bolster.

The object of the invention is to reinforce the bolster and provide in such reinforcement means for transmitting buffing stresses from the forward portions of the draft arms through the bolster to the sub-sills.

Preferred embodiments of the invention are hereinafter described and illustrated in the accompanying drawings, in which,

Figure 1 is a detail central vertical section of the underframing of a car crossing the bolster;

Fig. 2 is a detail plan view, partly in section, on the line 2—2 of Fig. 1;

Fig. 3 is a detail transverse section on the line 3—3 of Fig. 2;

Figs. 4 and 5 are detail sections similar to Fig. 1, showing modifications; and

Figs. 6 and 7 are views in perspective of the reinforcing elements shown in Figs. 4 and 5, respectively.

One of a pair of center sills is represented at 10. The upper plate of the bolster is shown at 11, and its lower plate at 12. Between the two members of the bolster there is located the usual filler block 13 apertured for the reception of a king pin, which passes through the plates of the bolster and through a filler block 14 above the same.

The draft arm 15 arches over the bolster, lying alongside of the sill, and having a flange 16 which underlies the sill and through which the attaching bolts 17 for securing the arm to the sill are passed. The forward portion of the draft arm 15 has a depending portion 18, which in the construction of Figs.

50 1 to 3 abuts against the upper plate 11 of the bolster. The sub-sill 19 is located below the sill 10 back of the bolster, and is secured in place by the bolts 17. The forward end of this sub-sill is in line with the rear face

55 of the bolster.

The reinforcing and stress-transmitting element is interposed between the upper and lower plates of the bolster below the draft arm 15 and is in rectangular form, comprising a top plate 20 bearing against the lower face of the bolster member 11, a bottom plate 21 bearing against the upper face of the lower bolster member 12, and side walls 22, 23, which bear, respectively, against the inner end of the depending portion 18 of the draft arm and the forward end of the sub-sill 19. This reinforcing element is also provided with a transverse vertical web 24, preferably joined, as shown, with the top, bottom and side walls. Depending from the lower corners of the reinforcing members are lugs 25, 26, which engage, respectively, the forward and rearward edges of the bottom plate 12 of the bolster. One of the bolts 17 for securing the draft arm 15 to the sill 10 passes down through the top and bottom plates of the reinforcing member and secures it in place. It will be understood that there is a draft arm 15 associated with each of the center sills, and a reinforcing member as described associated with each draft arm.

The bolt 17 for securing the reinforcing member in place binds the two members of the bolster securely to it. Buffing stresses are transmitted to the front wall 22 of the reinforcing member, and through this member to the buffing sill 19. These stresses are in part communicated to the lower bolster member 12 by the lug 25 and through this member to the lug 26, and thence through the reinforcing member to the sub-sill 19. The depending lugs 25, 26 overcome the tendency of the buffing stresses to distort the bolster by a twisting action.

In the form of construction illustrated in Figs. 4 and 6, the parts are, generally speaking, of the same construction. The reinforcing member, generally designated by the numeral 27, is however somewhat wider than the plates 11, 12 of the bolster, and its top and bottom plates 28, 29 are recessed in their upper and lower faces, respectively, to receive these bolster members. The depending portion 30 of the forward portion of the draft arm 15 is correspondingly shortened in order that it may abut against the reinforcing member 27, as is also the sub-sill 31. The action is the same as in the construction illustrated in Fig. 1 except that the

buffing stresses are in part transmitted directly to and through the upper plate 11 of the bolster.

In the construction illustrated in Figs. 5 and 7, the reinforcing member, generally designated by the numeral 32, is shown as having its upper plate 33 bearing against the lower face of the upper bolster member 11 and being transversely rabbeted adjacent to the side members 34, 35 to fit within and between shoulders 36, 37 formed in the lower face of the overarching portion of the draft arm, between which shoulders also interfits the bolster member 11. In other respects the reinforcing member 32 is the same in form as the reinforcing member 27 of Figs. 4 and 6. In the construction of Figs. 5 and 7 the buffing stresses are in part transmitted to and through the upper bolster member 20 and the top plate of the reinforcing element.

While preferred and practical forms of the invention are disclosed, various other changes of detail may be made without departing from its scope.

25 I claim as my invention:

1. In an underframing for cars, in combination, a bolster having upper and lower plates, a draft arm arching over the bolster and having a depending portion forward of the bolster and a reinforcing element interfitting between the bolster plates and bearing against the depending portion of the draft arm.

2. In an underframing for cars, in combination, a bolster having upper and lower plates, a draft arm arching over the bolster and having a depending portion forward of the bolster, a reinforcing element interfitting between the bolster plates and bearing against the depending portion of the

draft arm, and a sub-sill abutting against the rear face of the reinforcing element.

3. In an underframing for cars, in combination, a bolster having upper and lower plates, a draft arm arching over the bolster and having a depending portion forward of the bolster, and a reinforcing element interfitting between the bolster plates and having depending lugs embracing the lower plate, such element bearing against the depending portion of the draft arm.

4. In an underframing for cars, in combination, a bolster having upper and lower plates, a draft arm arching over the bolster and having a depending portion forward of the bolster, a reinforcing element interfitting between the bolster plates and having depending lugs embracing the lower plate, such element bearing against the depending portion of the draft arm, and a sub-sill abutting against the rear face of the reinforcing element.

5. In an underframing for cars, in combination, a bolster having upper and lower plates, a reinforcing element interfitting between such plates and extending forward and backward thereof, and a draft arm arching over the bolster and having transverse shoulders between which the reinforcing element interfits.

6. In an underframing for cars, in combination, a bolster having upper and lower plates, a reinforcing element interfitting between such plates and extending forward and backward thereof and being transversely recessed to receive the upper bolster plate, and a draft arm arching over the bolster and having transverse shoulders between which the reinforcing element interfits.

CHARLES J. NASH.
